ATTORNEY

UNITED STATES PATENT OFFICE.

HENRY B. WILSON, OF NEW YORK, N. Y.

DESIGN FOR A HANDKERCHIEF.

SPECIFICATION forming part of Design No. 15,569, dated November 18, 1884.

Application filed July 29, 1884. Term of patent 3½ years.

To all whom it may concern:

Be it known that I, HENRY B. WILSON, of the city, county, and State of New York, have invented a new and original Design for Handkerchiefs, of which the following is a specification, reference being had to the accompanying photographic illustration.

The leading feature of the design consists in the representation of the pieces A, shaped regularly, or nearly so, and the smaller irregularly-shaped pieces B, the whole being displayed to impart the appearance of a ground of patch-work, as shown in the accompanying drawings. (The pieces A may have any suitable ornament, C, and the effect will be enhanced if a portion of the pieces B contain rosettes D.) Along the contiguous edges of the pieces A B is the representation of stitches E, imparting the appearance of seams. The

representation of patch-work, which occupies 20 the greater portion of the handkerchief, is surrounded by a border, F.

What I claim is—

The design for handkerchiefs, the same consisting of the polygonal pieces A, shaped regularly, or nearly so, the smaller irregularly-shaped pieces B, and the representation of 25 stitches E along the contiguous edges of the said pieces A and B, the whole covering the entire central field of the handkerchief within 30 a surrounding border, as herein shown and described.

Witness my hand this 23d day of July, A. D. 1884.

HENRY B. WILSON.
